UNITED STATES PATENT OFFICE.

SAMUEL CLARK CROSS, OF WASHINGTON, DISTRICT OF COLUMBIA.

MINE-ANCHOR DEVICE.

Application filed June 20, 1923. Serial No. 646,649.

To all whom it may concern:

Be it known that I, SAMUEL CLARK CROSS, a citizen of the United States, residing at Washington, in the District of Columbia, have invented certain new and useful Improvements in Mine-Anchor Devices, of which the following is a specification.

My invention relates to devices for preventing sweeping of mines.

10 An object of my invention is to provide a device which will allow a mine sweeping cable to pass between the mine and its mooring without sweeping the mine.

15 Another object of my invention is to provide an anti-sweeping device which is so constructed that the sweeping cable will not become entangled with any joint or connection.

20 Still another object of my invention is to provide an anti-sweeping device for mines which will quickly and surely be rotated by the sweeping cable into operative position.

25 A still further object of my invention is to provide a device which may be easily and cheaply constructed, and will always be operative.

30 With these and other objects in view, which may be incident to my improvements, the invention consists in the parts and combinations to be hereinafter set forth and claimed, with the understanding that the several necessary elements comprising my invention, may be varied in construction, proportions and arrangement, without departing from the spirit and scope of the 35 appended claims.

35 In order to make my invention more clearly understood, I have shown in the accompanying drawings means for carrying 40 the same into practical effect, without limiting the improvements in their useful applications to the particular constructions, which for the purpose of explanation, have been made the subject of illustration.

45 In the drawings:

Figure 1 is a view in side elevation of my device just at the moment that the mine sweeping cable is in position to operate the same;

50 Fig. 2 is a view in side elevation showing the position taken by the parts when the

mine sweeping cable has just entered the by-pass;

Fig. 3 is a view in side elevation illustrating the position of the parts just as the mine 55 sweeping cable is leaving the by-pass;

Fig. 4 is a longitudinal view in detail of the operating mechanism;

Fig. 5 is a cross sectional view taken on the line 5—5 of Fig. 4, looking in the direction 60 of the arrows;

Fig. 6 is a cross sectional view taken on the line 6—6 of Fig. 4, looking in the direction of the arrows;

Fig. 7 is a cross sectional view taken on the line 7—7 of Fig. 4, looking in the direction 65 of the arrows;

Fig. 8 is a cross sectional view taken on the line 8—8 of Fig. 4, looking in the direction of the arrows.

70 Referring to the drawings for a detailed description, I have shown in Figs. 1, 2 and 3, a mine 1, having a connecting staple 2 fastened to its surface. To the connecting staple 2 is connected a link 3, which in turn is connected to a link 4. The lower end of the link 4 pivotally holds the antimine sweeping device, which will later be described. Below the antimine sweeping device is a mooring cable 5, whose lower end 80 is fastened to an anchor block 6.

75 The antimine sweeping device comprises a support member 7 at whose upper corner is formed a hole 8 in which the link 4 is pivoted. The support member 7 is formed with a guide track 9 therein, formed on either side of the support member 7. The guide tracks 9 are constructed by forming the support member 7 with upstanding ridges 11. The support member 7 has an 85 upstanding core piece 12 on either side. The guide tracks 9 are formed between the upstanding core pieces 12 and the ridges 11. The support member 7 is roughly of triangular shape and has a catch lip 13 at one 90 edge. The under side of the support member 7 has a slightly downwardly slanted riding surface 14. At the lower end of the riding surface 14 the support member 7 is formed with a by-pass 15 to permit the mine 95 sweep cable to by-pass to the position, as shown in dotted lines in Fig. 4, up into the 100

center of the core pieces 12. To prevent the mine sweep cable from riding over the by-pass, the support member 7 is formed with a guiding lip 16 which projects downwardly a considerable distance below the riding surface 14.

A portion of the support member 7, which lies within the guide track 9, is cut away at 17, and a latch 18 is adapted to project into this cut-away portion of the guide track. The latch 18 is pivoted to the support member 7 at 19. The lower side of the latch 18 rests for a portion of its length against a shoulder 21 formed on the support member 7, and a compression spring 22 is mounted in the cut-away portion 17 with its upper end bearing against the support member 7 and its lower end against the latch 18, normally holding the latch 18 in the position shown in Fig. 4.

A link member 23 is formed with two parallel arms 24, which have bowed surfaces 25 for the purpose of making sure that the apparatus will turn in the operative position when these bowed surfaces contact with the mine sweeping cable. The bowed surfaces operate to rotate the device when the cable touches these surfaces. Below the link 23, and preferably integrally formed therewith, is a bowed connection 26 which is distorted to present a bowed surface to any mine sweeping cable, thereby causing the device to rotate into operative position. The bowed surfaces 25 and the bowed surface 26 co-operate together to make certain that the device shall always move into operative position.

The parallel arms 24 of the link member 23 have mounted near their upper extremities two shafts 27, which are adapted to be held to the arms 24 by means of bolts or pins which pass through apertures 28 in the shafts 27. The shafts 27 are provided on their inner extremities with heads 29 and rollers 31. The rollers 31 are mounted on the shafts 27 and held against axial displacement between the heads 29 and the support arms 24. The rollers 31 travel in the guide tracks 9, as is illustrated in Fig. 4. The lower extremity of the connection 26 is formed with a swivel shaft 32 thereon, which fits through a hole 33 formed in a link 34. A head 35, which may be formed by riveting, holds the swivel shaft 32 in the hole 33 of the link 34. The link 34 is connected to another link 36, which is in turn suitably connected to the mooring cable 5. The link 36 has fitted therearound a guard 37, which is preferably formed of heavy sheet metal and extends upwardly to a point adjacent to the lower end of the link 34. This guard 37 prevents the mine sweeping cable from becoming entangled with the parts just described.

The swivel joint between the connection

26 and the link 34 permits the anti-sweeping device to be easily rotated into operative position at all times.

In operation, a mine sweeping cable 38 will pass along until it comes in contact with the connection between the mine and its mooring. The cable 38 will slip along the connection and when it strikes the bowed surface 26, the bowed surface 26 will cause the anti-sweeping device to be rotated into operative position, provided it is not already in that position. (See Fig. 1). The mine sweeping cable 38 will then slide up past the catch lip 13. The cable in passing along drawn between the mine sweeping boats, will slide down the surface 14 of the support member 7, and push before it the link member 23. The rollers 31 of the link member 23 will pass along the guide tracks 9, as indicated in dotted lines in Fig. 4, and the mine sweeping cable 38 will engage with the guiding lip 16, and will pass up into the by-pass 15, as indicated in Fig. 2. The rollers 31 then pass on down below the cable 38, but will not pass out through the by-pass 15, because they are too large to pass through an aperture of this size.

The mine sweeping cable 38 will pull the device over into the position shown in Fig. 3, in which position the rollers 31 have passed back into the position illustrated in Fig. 4, where they are prevented by the latch 18 from traveling backward in the direction from which they have come. The latch 18 is adjusted to be pressed by the spring 22 to a sufficient degree to operate the latch, but the spring is not strong enough to prevent the rollers 31 from readily raising the latch 18 in the cycle of operation just described. In the position shown in Fig. 3, the mine sweeping cable 38 is leaving the by-pass 15, and the mine and accompanying mechanism will then take up its normal position, as indicated in Figure 1.

While I have shown and described the preferred embodiment of my invention, I wish it to be understood that I do not confine myself to the precise details of construction herein set forth, by way of illustration, as it is apparent that many changes and variations may be made therein, by those skilled in the art, without departing from the spirit of the invention, or exceeding the scope of the appended claims.

I claim:

1. In a mine mooring device, the combination with a mine, of a mooring therefor, a connection between the mooring and the mine, a mine sweep slip device in such connection operative in certain positions only, and having a by-pass therein, a swivel joint in such connection comprising links, one of which has a swivel socket, and the other of which has a guard, and means for directing

a mine sweep through said by-pass for preventing the sweeping of the mine.

2. In a mine mooring device, the combination with a mine, of a mooring therefor, a connection between the mooring and the mine, means operative in certain positions only comprised in such connection, permitting a mine sweep to pass between the mine and the mooring, and a swivel joint in such connection comprising links, one of which has a swivel socket and the other of which has a guard for preventing the mine sweep from catching in the links. 70

3. In a mine mooring device, the combination with a mine, of a mooring therefor, a connection between the mooring and the mine, a mine sweep slip device in such connection operative in certain positions only, and a plurality of elements mounted one 80 above the other comprised in the connection both tending to rotate the slip device into operative position.

4. In a mine mooring device, the combination with a mine, of a mooring therefor, a connection between the mooring and the mine, a mine sweep slip device in such connection operative in certain positions only, and a plurality of bowed surfaced elements in the connection for rotating the slip device 85 into operative position. 90

5. In a mine mooring device, the combination with a mine, of a mooring therefor, a connection between the mooring and the mine, a mine sweep slip device in such connection operative in certain positions only, and two bowed surfaced elements, one mounted adjacent to and above the other for rotating the slip device into operative 100 position. 105

6. In a mine mooring device, the combination with a mine, of a mooring therefor, a connection between the mooring and the mine, a support member in said connection having a by-pass, a guide track in said support 110 member, a link member operated by a mine sweep and adapted to move in said guide track, and a bow surface on said link member adapted to co-operate with the mine sweep to move the mechanism into operative 115 position. 120

7. In a mine mooring device, the combination with a mine, of a mooring therefor, a connection between the mooring and the mine, a support member in said connection 125 pivotally connected to the mine and having a by-pass, a guide track in said support member, a guiding lip on the support member for directing a mine sweep into the by-pass, a link member, outstanding means on the link member adapted to move in said guide track, and means for permitting a complete cycle of movement of the link member in one direction only. 130

8. In a mine mooring device, the combination with a mine, of a mooring therefor, a connection between the mooring and the mine, a support member in said connection 135

connection between the mooring and the mine, a support member in said connection pivotally connected to the mine and having a by-pass, a guide track in said support member, a guiding lip on the support member for directing a mine sweep into the by-pass, a link member, outstanding means on the link member adapted to move in said guide track, and a latch co-operating with said means for permitting a complete cycle of movement of the link member in one direction only. 75

9. In a mine mooring device, the combination with a mine, of a mooring therefor, a connection between the mooring and the mine, a support member in said connection pivotally connected to the mine and having a by-pass, a guide track in said support member, a guiding lip on the support member for directing a mine sweep into the by-pass, a catch lip on the support member, a link member, outstanding means on the link member adapted to move in said guide track, and a latch co-operating with said last named means for permitting a complete cycle of movement of the link member in one direction only. 85

10. In a mine mooring device, the combination with a mine, a mooring therefor, a connection between the mooring and the mine, a support member in said connection pivotally connected to the mine and having a by-pass, a guide track in said support member, a guiding lip on the support member for directing a mine sweep into the by-pass, a catch lip on the support member, a link member, a bow surface on the link member for rotating the device into operative position, outstanding means on the link member adapted to move in said guide track, and a latch co-operating with the last named means for permitting a complete cycle of movement of the link member in one direction only. 100

11. In a mine mooring device, the combination with a mine, of a mooring therefor, a connection between the mooring and the mine, a support member in said connection pivotally connected to the mine and having a by-pass, a guide track in said support member, a guiding lip on the support member for directing the mine sweep into the by-pass, a catch lip on the support member, a link member, rollers on the link member traveling in the guide track, a latch co-operating with the rollers for permitting a complete cycle of movement of the link member in one direction only, and a plurality of bowed surfaced elements in the connection for bringing the device into operative position. 110

12. In a mine mooring device, the combination with a mine, of a mooring therefor, a connection between the mooring and the mine, a support member in said connection 125

having a by-pass, a guide track in said support member, and a link member operated by a mine sweep and adapted to move in said guide track, whereby the sweeping of the mine is impeded.

13. In a mine mooring device, the combination with a mine, of a mooring therefor, a connection between the mooring and the mine, a support member in said connection

having a by-pass, a guide track in said support member, a link member operated by a mine sweep and adapted to move in said guide track, and means adapted to co-operate with the mine sweep to move the mechanism into operative position.

15

In testimony whereof I affix my signature.

SAMUEL CLARK CROSS.
